Attorney.

UNITED STATES PATENT OFFICE.

MORGAN R. BUTLER, OF WAUKESHA, WISCONSIN.

MATERIAL-HANDLING EQUIPMENT.

Application filed May 26, 1923. Serial No. 641,703.

This invention relates to certain new and useful improvements in material handling equipment and refers more particularly to a measuring hopper for stone, sand, grain or any other type of material.

One objection to that type of measuring hopper now in general use is the inability of readily adjusting its cubic capacity and while they have had more or less a degree of adjustability, the adjustment is a difficult one to make and when once set, is maintained for a considerable period of time. With this objection to the adjustment of the present type of material measuring hopper in mind, it is an object of this invention to provide means for obtaining the ready adjustment of the hopper wherein the same may be quickly adjusted to any point between its maximum and minimum cubic capacity.

This invention has for another of its objects to provide means for indicating the cubic capacity to which the hopper has been adjusted.

It is a further object of this invention to provide a material measuring hopper having means remote therefrom and positioned at a point convenient to the operator for readily adjusting the cubic capacity of the hopper.

A still further object of this invention is to provide a measuring hopper having a plurality of spaced discharge openings and a plurality of connected gate members therefor adapted, upon opening movement, to be positioned intermediate of the openings whereby a maximum discharge area is provided with a minimum movement of the gate members.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the phys-

ical embodiment of my invention constructed according to the best mode I have so far devised for the practical application of the principles thereof, and in which:

Figure 1 is a side view of a measuring hopper embodying my invention, parts thereof being broken away and in section to more clearly illustrate details of construction, and

Figure 2 is a view, partly in transverse section and partly in elevation, taken through Figure 1 substantially on the plane of the line 2—2.

Referring now more particularly to the accompanying drawing, in which like numerals designate like parts throughout the several views, the numeral 5 designates the uprights or standards of a supporting frame 6, above which is mounted a supply bin, not shown, having a discharge opening registering with an opening or passageway 7 in the supporting frame, the same leading to the upper end 8 of a measuring hopper 9.

The measuring hopper comprises an upper section 10, a lower section 11 and preferably one or more intermediate sections 12, said sections being adapted to telescope one within the other to adjust the cubic capacity of the hopper. Suspended from frame 6 are a plurality of guide members 13 between which the hopper is mounted and the lower section 11 of the hopper is provided with transversely extending beams 14 having their ends projecting beyond the hopper and engageable with the adjacent guide members 13 to guide the hopper as it is adjusted. As disclosed in the drawings, the beams 14 are positioned upon the inner and outer sides of the beams 13, the purpose of which will be hereinafter more fully apparent as the description proceeds.

The lower portion 11 of the hopper is movable toward and away from the supporting frame 6, to regulate the cubic capacity of the hopper, by cable members 15 having their ends connected with the adjacent ends of the beams 14 by eye-bolts 16 and their other ends connected with drums 17 mounted on a shaft 18 journaled in bearings 19 carried by an adjacent pair of uprights 5. The cables 15 are preferably guided over guide

sheaves 20 journaled in brackets secured to the supporting frame.

Shaft 18 has a ratchet wheel 21 secured thereto and a lever 22 freely and rotatably mounted thereon adjacent the ratchet and carrying a pawl or dog 23 engageable with the teeth of the ratchet wheel 21 whereby shaft 18 may be readily rotated to wind cables 15 on the drums 17 and consequently telescope the hopper sections to decrease the cubic capacity thereof or whereby the pawl 23 may be disengaged from the ratchet wheel to permit the extension of the hopper sections to increase the cubic capacity thereof.

In order to visually indicate the cubic capacity of the hopper at any adjustment an indicating finger or hand 24 is carried by the lower section 11 which cooperates with a scale 25 secured to an adjacent guide member 13, the scale indicating the cubic capacity of the hopper at any position of the parts thereof to thus permit the ready adjustment of the hopper to any desired cubic capacity.

In measuring hoppers it is highly desirable that they be capable of instantly discharging their contents, which necessitates the provision of a discharge opening of maximum area. In the past it has been difficult to provide a discharge opening of the desired area, as to do so required a control gate, the opening movement of which was equivalent to the width of the discharge opening. Such a structure, in the past, has been cumbersome as to provide a single control gate having the desired opening movement necessitated too great a movement of the gate.

In this invention, I overcome this objectionable feature by providing a plurality of discharge openings 26, preferably of elongated shape and spaced apart a distance not less than the width of each opening, adapted to be closed by gate members 27 connected by a single operating rod 28 and having their edges guided on angular members 29 secured to the extended side wall portions 30 of the hopper sections 11 and the end members 14.

A link 30' pivotally connects one end of bar 28 with a lever 31 having its upper end pivoted, as at 32, to a bracket 33' carried by the hopper member 11 and its lower free end 33 positioned so that an operator can readily actuate the same to move the gate members 27 to and from closed position. In Figure 1 the gate members are illustrated as in closed position and a movement of lever 31 to the left with reference to Figure 1 moves the right-hand gate 27 within the space 34 between the discharge openings and the left-hand gate 27 to the left of its discharge opening, as will be readily obvious. During the movement of the valve to its opening position, it will be observed that

the beams 14 are forced in a horizontal plane against the perpendicular faces of the beams 13, thus limiting the movement of the lower section of the hopper and holding the same at all times in alignment with its upper section. With this construction a discharge area equal to the combined openings 26 is provided and the total movement of the operating bar 28 required to effect full opening of the discharge is but one-half that required if but a single discharge opening were employed.

The measuring hopper and the supply bin, not shown, may be readily connected and disconnected by a valve member 35 carried by an operating rod 36 and movable across opening 7 by a lever 37 medially pivoted, as at 38, to a bracket 39 secured to the supporting frame. The upper end of lever 37 is pivotally connected with the bar 36 by a link 40.

When it is desired to measure a predetermined volume of material, as for example one and one-half cubic yards, the operator adjusts the hopper by means of the ratchet lever 22 to register the pointer 24 with the one and one-half cubic yards designation on the scale 25, then opens gate 35 by swinging the lower end of lever 37 to the right with reference to Figure 1 and when the container is filled, gate member 35 is closed and the discharge gates 27 opened to empty the hopper.

What I claim as my invention is:

1. In a device of the class described, the combination of a supporting member and a two-part adjustable hopper connected thereto, guide elements secured to said supporting member and between which said hopper is positioned, a control valve and its operating means carried by the movable part of said hopper, said movable part being movable with respect to said guide elements, and said movable part bearing against said guide elements and being retained in alignment with its stationary part during the movement of the valve to its opening position.

2. In a device of the class described, the combination of a supporting member and a collapsible measuring hopper connected thereto, said hopper being composed of fixed and movable parts, a rectangular frame depending from said supporting member and within which said hopper is positioned, a control valve for the lower part of said hopper and operating means therefor carried by the latter, and said lower part of the hopper being retained in vertical alignment with its fixed part by said rectangular frame during the opening movement of the valve.

3. In a device of the class described, the combination of a supporting member and a collapsible measuring hopper connected thereto, guide elements arranged in pairs about said hopper and between which its

lower portion moves, supporting bars for the lower portion of said hopper, said bars being positioned upon the inner side of one pair of guide elements and upon the outer side of the other pair, a control valve and its operating means carried by the lower portion of said hopper and the lower part

of said hopper being retained in vertical alignment with its upper part during the opening movement of the valve by the engagement of the supporting bars with the guide elements. 10

In testimony whereof I affix my signature.
MORGAN R. BUTLER.
